FLATIRON SUPPORT MECHANISM

Paul Cureton, Long Beach, Calif.

Application July 7, 1947, Serial No. 759,409

2 Claims. (Cl. 38—79)

1

This invention relates to flat irons and has particular reference to means mountable on such iron for maintaining the iron in an elevated position relative to the ironing board or other supporting surface therefor, when not in use. To this end the invention consists in the combinations hereinafter fully described and illustrated in the pending drawings, of which:

Fig. 1 is a side elevational view of an electric iron embodying the invention;

Fig. 2 is a view of the underside of the device of Fig. 1;

Fig. 3 is a side elevational view showing the device in a different position of adjustment and with additional features embodied therein; and

Fig. 4 is a fragmentary detail view of important elements of the invention.

In the form illustrated in the drawings, the device of the invention is mounted on a conventional type of electric iron including a body 1 and a handle 2. The latter is secured to arms 3, 4 rising from the body in the usual commercially well known manner.

As indicated in the drawings, a bracket 5 extends rearwardly from the body 1. This bracket is shaped to receive a short rod or stem 6 which, in turn, forms part of the supporting device of the invention. This device is composed of two main portions, one of which is a forwardly extending bifurcated frame 7 and the other a rearwardly projecting bail 8. These parts are rigidly secured to the stem 6 and are mounted for rotation within bearings at the end of the bracket 5.

In addition to the foregoing, it is noticed that a pair of short studs 9 project forward from the stem 6 and that they terminate at the front end in ball-shaped heads 10. A second pair of ball-shaped members 11 is rigidly secured to the body of the iron by means of short studs 12. A powerful compression spring 13 bridges a space between each set of ball heads 10 and 11 and these springs control the position of the supporting device relative to the iron in the following manner. The bifurcated frame 7 forms the foot upon which the iron comes to rest when it is in the upwardly tilted position of Fig. 3 and it is returnable to the position of Fig. 1, within the contour of the iron, so as to be entirely out of the way while the latter is in operation. The springs 13 are designed yieldingly to maintain the support firmly in either position. In order to attain this result, it is necessary that the two sets of ball heads 10, 11 are correctly positioned relative to each other. Illustrative of this relation, I have shown the ball heads 11 and the stem 6 inter-

2

sected by a horizontal line A—A and it is noted that the ball heads 10, in the position indicated in Fig. 1, take a position slightly above this intersecting line while, in Fig. 3, they have moved to a position somewhat below this line.

As stated, the supporting device normally takes the out of the way position indicated in Fig. 1 and when it is desired to tilt the iron into the position of Fig. 3 it is merely required to tip the iron backward until the end of the bail 8 contacts the ironing board or other supporting surface whereupon slight continued pressure causes the bail to swing upward until the ball heads 10 pass over the dead center line A. Pressure of the springs 13 then causes the foot 7 to assume the projected position indicated in Fig. 3. The iron may be safely left in this position until again required for use, and it will rest solidly on the foot 7 at a sufficient distance above the ironing board to eliminate all danger of scorching.

As stated, the foot 7 moves into position within the contour of the iron when not in use and it is to be noted that the sole plate 14 of the iron is recessed on each side freely to receive the foot. In order more correctly to position the foot in this position, it may be well to provide stop pins 15 which serve to prevent direct contact of the upper surface of the foot with the body of the iron and so assist in forming an air space about the prongs of the foot designed to prevent undue heating of the foot.

The supporting device above described forms a very simple and effective means of maintaining an iron in upwardly tilted position and, as stated, it is operable to tilt on the iron by contact of the heel 8 with the surface of the ironing board. When it is again desired to return on foot to the position of Fig. 1, it is merely required to tilt the iron forward, whereupon pressure against the iron will cause the foot to swing over the dead center and the springs 13 to return it to its withdrawn position. Means is provided for limiting outward movement of the foot 7 and such means is in the drawing shown in the form of an arm 16 of the stem 6 which comes to a stop against the bracket 5 when the foot is projected. It may be found desirable to modify the projecting movement of the foot and this may be done by placing an adjusting screw 17 in the arm 16.

It may, however, at times be preferred manually to operate the supporting device independently of any tilting movement of the iron and sub-

sequent pressure against the supporting surface and this may be done in the following manner:

In a recess 2^a of the handle is mounted a lever 20, on a pivot 21, and a link 22 is journaled on the end of this lever as indicated in 23. This link is extended downward, and the lower end thereof is pivotally secured to the end of a stud 24 which is placed on the stem 6 intermediate the studs 9. A finger piece 25 is secured to the front end of this lever and it extends normally below the surface of the handle 2, substantially as indicated in Fig. 3. When it is required to move the foot 7 into the projected position of Fig. 3, it is merely required to lift the iron away from the board and to grip the handle 2 with sufficient force to press the finger piece 25 into the recess 2^a thereby to cause the stem 6 to rotate until the ball heads 10 pass below the dead center whereupon pressure of the spring 13 causes the supporting frame to swing into the position of Fig. 3. This operation may be further facilitated by placing a compression spring 26 on a bracket 27 of the arm 4 to bear against the under surface of the lever 20. The tension of this spring will counteract the pressure exerted by the springs 13 sufficiently materially to reduce the pressure required against the finger piece 25 to swing the supporting device into open position. It may be well to place a pilot 28 in the lever 20 to assist in maintaining the spring 26 correctly aligned relative thereto. But I wish it understood that this finger operated foot projecting mechanism is merely illustrative of manual projecting means and that other arrangements may be substituted for this purpose.

When this lever controlled mechanism is employed to project the supporting foot of the iron, it is to be noted that the bail 8 may be entirely eliminated since it is no longer essential to the operation thereof. This will have the advantage of reducing the manufacturing cost of the iron.

As above stated, the springs 13 ride on the ball heads 10, 11, against which they exert considerable pressure. In order to eliminate friction and also so as to better support the ends of the springs, I have introduced bearing cups 18 which ride on the heads 10, 11 and are recessed at 19 to form seats for the ends of the springs, all as best shown in Fig. 4.

While I have above described preferred forms of the invention, it is not intended thereby to limit the invention thereto but the right is reserved to embody further modifications within the scope of the claims hereto appended. Nor is the device limited to use on the conventional type of electric iron illustrated in the drawings but is equally well adapted for use on any of the newer models of irons now appearing on the market.

I claim:

1. The combination with a flat iron operable on a support and having recesses at the bottom side edges thereof, of a bracket rearwardly extending from the body of the iron and terminating in bearings, a bifurcated frame transversely mounted for rotation within said bearings and having prongs forwardly extending therefrom normally to lodge within said recesses, a bail rearwardly extending from the frame for contact with said support upon backward tilting movement of the iron, continued tilting movement thereof causing the bail and frame to swing on the frame pivot thereby to move the frame out of the said recesses, studs forwardly projecting from the frame in continued alignment with said bail, studs rearwardly projecting from the iron body, compression springs between the iron body studs and the frame studs normally exerting pressure to maintain the frame seated within said recesses and in the opposite direction upon starting said frame swinging movement.

2. The combination with a flat iron operable on a support and having recesses at the bottom side edges thereof, of a bracket rearwardly extending from the body of the iron and terminating in bearings, a bifurcated frame transversely mounted for rotation within said bearings and having prongs forwardly extending therefrom normally to lodge within said recesses, a bail rearwardly extending from the frame for contact with said support upon backward tilting movement of the iron, continued tilting movement thereof causing the bail and frame to swing on the frame pivot thereby to move the frame out of the said recesses, adjustable means limiting outward movement of the frame, studs forwardly projecting from the frame in continued alignment with said bail, studs rearwardly projecting from the iron body, compression springs between the iron body studs and the frame studs normally exerting pressure to maintain the frame seated within said recesses and in the opposite direction upon starting said frame swinging movement.
